[57] **CLAIM**

The ornamental design for the lordotic artificial spinal fusion
 implant, as shown and described.

DESCRIPTION

FIG. 1 is a perspective view of a lordotic artificial spinal fusion implant showing my new design with the sliding door
 in a partially open condition;
 FIG. 2 is a top plan view thereof, the bottom plan view being
 a mirror image that shown;
 FIG. 3 is a left side elevational view thereof;
 FIG. 4 is a right side elevational view thereof;
 FIG. 5 is a rear elevational view thereof;
 FIG. 6 is a front elevational view thereof; and,
 FIG. 7 is a fragmentary portion of the top plan view on a
 greatly enlarged scale of the area within the circled region 7
 of FIG. 2.
